ENERGIZER

Clifford E. Roberts, Joppa, Md., assignor to The
Glenn L. Martin Company, Middle River, Md., a
corporation of Maryland

Application February 23, 1942, Serial No. 432,093

2 Claims. (Cl. 138—30)

This invention relates to an energizer and more particularly to a hydraulic fluid accumulator for particular use with aircraft to insure a source of hydraulic pressure in cases of emergency.

It is well known that in modern aircraft many items of equipment therein, such as locks, centering devices, brakes, retractable landing gears and the like, are operated by means of hydraulic fluid pressure. These systems are maintained at the desired pressure by means of power driven pumps, pistons and the like. In systems of this character, it is desirable to provide them with so called pressure equalizers so that in normal use, the pressures of the two fluids used, such as air and oil, will be equalized and at the same time form a source of emergency energy available for operating the fluid controlled apparatuses if the main pressure supply is damaged.

In the present invention, an outer steel alloy bottle or container is provided with a valve means for filling the same with air. The bottle is fitted with an interior, collapsible, synthetic rubber or plastic impregnated fabric envelope or cell connected to a source of oil pressure so that when oil is introduced into the interior envelope, the envelope unfolds or expands and compresses the surrounding air within the steel bottle to a degree where the air pressure is equal to the interior pressure of the oil within the rubber bag. When such a point is reached, the air and oil pressures in the system are equalized, and in the event that the hydraulic fluid pressure is decreased, as by rupture of the oil pump system, the compressed air in the bottle is available for operation of the hydraulic devices normally acted on by the oil pressure.

In the accompanying drawing:

Fig. 1 is a sectional view, partly in cross section, showing the inner, collapsible, rubber bag in deflated condition.

Fig. 2 is a similar view after the oil bag has been inflated and the air and oil pressures have reached a point of equilibrium.

Fig. 3 is a vertical cross section through the bottle and inflated oil bag.

Specifically, the invention contemplates using a strong, light-weight steel alloy bottle 1 suitably tapped at 2 for the insertion of an air line 3 controlled by valve 4. The opposite end of the bottle is provided with an enlarged opening 5 and a suitable coupling 6 joined to the hydraulic fluid or oil pressure line 7 which leads to the hydraulic system of the aircraft.

An inflatable, elongated, tubular bag or envelope 8 is attached to the inner portion of the coupling 6 and communicates therethrough to the conduit 7. This interior bag is preferably formed of synthetic, oil resistant, plastic or rubbery material such as neoprene, Thiokol, nylon or the like. It may also be constructed of an

elastic or non-elastic fabric impregnated with an oil resistant material having the properties of these products.

The bottle is charged through its valve with compressed air, while the inner envelope is in deflated condition, and in use, when the bag is subjected to hydraulic fluid or oil pressure, it will inflate and compress the air in the bottle to a degree wherein the hydraulic fluid pressure is equalized with the air pressure.

Thus, in the event of an emergency, as where the oil pressure line from the pump is ruptured or the oil pump supplying this pressure ceases to function, the pilot of the aircraft has instantly available a source of compressed air pressure for energizing the hydraulic fluid in the system to operate his retractable landing gear or other instruments by reason of the energy of the compressed air within the steel bottle compressing the envelope containing the hydraulic fluid.

A further advantage of the present device is its ability to protect sensitive hydraulic mechanisms by preventing hydraulic hammer and dampening flutter in the hydraulic system.

What I claim is:

1. An emergency hydraulic pressure supply comprising a hollow cylindrical container, an impervious inflatable bag enclosed thereby, said container having an enlarged opening in one end thereof, a removable fitting for said opening to which the hydraulic pressure line is secured, a relatively small opening in the opposite end and a conduit connected thereto, through which compressed air may be introduced into the space between said container and said bag, an inflatable, impervious bag for receiving the hydraulic fluid attached to said fitting and extending into the said container, the interior of said bag communicating with the hydraulic pressure system through said fitting.

2. An emergency hydraulic pressure supply comprising an elongated hollow container having a small fitting at one end for the introduction of compressed air and a relatively large opening at the other end, a removable fitting in said large opening having a passage therethrough communicating with the hydraulic pressure system, an impervious, inflatable, elongated bag generally similarly shaped to conform with the internal contour of said container mounted on and removable with said fitting, said bag forming two chambers within the container, the outer one having air under pressure and the inner one having hydraulic fluid whereby the compressed air forces the hydraulic fluid from the bag to the hydraulic pressure system upon the failure of the normal hydraulic pressure source.
